UNITED STATES PATENT OFFICE

WILLIAM GAST, OF PHILADELPHIA, PENNSYLVANIA

OPEN-HEARTH FURNACE

Application filed June 23, 1921. Serial No. 479,763.

Some of the objects of the present invention are to provide an improved furnace construction whereby there is an increased saving of fuel and equipment as compared to 5 furnaces now in operation; to provide means for reducing losses by radiation in open hearth furnace operation; to provide means for controlling the gas supply to the furnace of the open hearth type and proportioning 10 the gas according to conditions in the furnace; to provide means for giving the mixed air and gas a relatively high velocity when burning prior to entering the heating chamber of the furnace; to provide means for delivering the air from the respective generators to points exterior of the heating chamber where it mixes with the incoming gas and burns with complete combustion prior to 15 passing through the furnace heating chamber; to provide improved draft conditions in an open hearth furnace; to provide means for promoting complete combustion of the gas products; and to provide other improvements as will hereinafter appear.

20 In the accompanying drawings, Fig. 1 represents a sectional elevation of a furnace having embodied therein one form of the present invention; Fig. 2 represents a horizontal section of one end of the furnace and its 25 adjuncts; and Fig. 3 represents a section on line 3—3 of Fig. 1.

Referring to the drawings, an open hearth furnace 10 having the customary hearth 11 is shown embodying at two opposite ends 30 one form of the present invention. Since the construction at these ends is preferably similar, this description will be limited to one end and similar reference numerals applied to like parts at the opposite end.

40 In conjunction with the operation of the furnace 10 it is desirable, to obtain the most advantageous results, to provide a regenerator 12 of the type shown in my Patent No. 1,361,709 wherein the baffle walls 13 of the checker chamber are arranged parallel to the side walls of the furnace 10 in such a position as to discharge air to the furnace 10, and upon reversal of furnace operation to receive products of combustion from the furnace 10.

45 Flues (not shown) lead from the customary

stack and air valve to the respective regenerators 12 at the two ends of the furnace 10 as will be understood.

For the purpose of conveying air from a 55 regenerator 12 to the furnace 10, a passage 16 is provided which extends transversely of the end of the furnace 10 and opens into a vertical shaft 17 leading to and in communication with a flame guide throat 18 arranged to discharge into the furnace 10 upon 60 the bath on the hearth 11. The bounding wall 20 of the throat 18 is preferably of tapered form having the smaller end toward the bath and its larger end forming a continuation of a similarly tapered arch 21 65 which forms a part of the top of the air shaft 17 for a purpose which will presently appear.

In order to produce the desired combustion, a gas nozzle 22 is provided which is 70 mounted for sliding movement through the furnace wall 23 in coaxial relation with the throat 18 so that the supplied gas will be discharged directly across the air shaft 17 to there mix with the air and produce the desired combustion and intense heating flame. The discharge end of the nozzle 22 is 75 preferably tapered to conform to the taper of the partially encircling arch 21 and as it is normally spaced from the said arch 21, the air 80 traversing this space will cause, with the nozzle 22, an injector effect to produce an effective velocity as well as a thorough mixing of the air and gas.

To protect that portion of the nozzle 22 which is exposed to the heat zone, it may be encased in a water jacket 24 in a well known manner and provided with a fire brick lining 25. The nozzle 22 is mounted for sliding movement upon a fixed head 26 which is in communication with a gas supply conduit 27 and is provided with an outlet port 28 arranged to register with an inlet port 30 formed in the body of the nozzle 22 and communicating with the tapered bore 31 of the said nozzle 22. The arrangement is such that the quantity of gas can be regulated in accordance with the position of the nozzle 22 with respect to the throat 18, thus when a full gas supply is required the two ports 28 and 30 register to admit a maxi- 90 95 100

mum gas supply, and when conditions require less gas the nozzle 22 is moved to partially cut off the inlet port 30 so that the gas is proportioned in a definite manner and according to requirements.

For more intimately mixing the air and gas at the nozzle, an auxiliary air jet 32 is provided, this being preferably located in the bore 31 of the nozzle 22 with an inlet 33, through the wall of the nozzle 22, and an outlet 34 directed toward the main nozzle outlet 35. This jet 32 is brought into operation as soon as its inlet 33 is moved into the air shaft 17, and as a result the gas is thoroughly mixed and the burning mixture given the desired velocity. Any desired means may be employed for shifting the nozzle 22 to its operative position, such for example as a movable rack 36 fixed to the nozzle 22 and meshing with a pinion 37 arranged to be actuated by a hand wheel 38, the latter two members being carried by the head 26 or other fixed part.

For the purpose of directing the products of combustion to a regenerator 12, upon reversal of the furnace, the air shaft 17 serves as one channel for the products while two separate channels 40 and 41 are arranged to communicate with the furnace 10 at opposite sides of the throat 18 and lead downwardly to a lateral passage 42 which is in communication with the same end of the regenerator 12 as the air passage 16, though in this construction an end wall 43 is built up from the bottom of the regenerator across the passage 42 to support an arch 44 which joins a depending baffle wall 45 across the top portion of the passage 42. This arch 44 is provided with an opening 46 arranged to be opened and closed by a damper 47 or any other suitable valve means, which may be operated in any suitable manner. This construction provides means whereby the products of combustion may enter the regenerator 12 when the valve or damper 47 is open, and whereby all the air is directed from the regenerator to the air shaft 17 when the damper 47 is closed.

In the operation of the furnace when one regenerator 12 is supplying air to the furnace the damper 47 is closed so that all the air passes through passage 16 and up the shaft 17 where it mixes with the gas and burns prior to entering the throat 18 giving a high velocity flame due to the tapering inlet about the nozzle 22. The effect is that of an injector and causes the flame to be drawn into the throat with a greater acceleration than would be produced by the nozzle 22 alone. With the auxiliary jet 32 in operation the gas and air are intimately mixed to produce an intense flame and a complete burning of the products outside of the throat 18 so that the usual losses due to incomplete combustion are eliminated.

When the furnace is reversed the valve or damper 47 of the regenerator 12, above described, is opened to bring the additional

channels 40 and 41 into use in order to cause the products of combustion to pass through the slag pockets into the regenerator. It will be understood, also, that the air uptake shaft 17 now becomes a downtake for other portions of the products of combustion passing to the same regenerator. The operation of the opposite end of the furnace is the same, the products and air for the respective regenerators being controlled in the usual manner by the stock valve.

From the foregoing it will be apparent that a construction is provided whereby fuel is supplied directly to either end of an open hearth furnace with a minimum of travel and consequent saving in heat units which are ordinarily lost by radiation. With the use of producer gas, a straight, direct well insulated gas main serves to deliver the gases by the quickest and shortest route to the furnace, so that frictional and temperature losses are reduced to a minimum and a considerable fuel-saving results.

In furnaces as at present in use, when the gases pass through the regenerators, the checkers are more quickly clogged up with the result that the furnace commences to slow down, yet it is still maintained in operation even though there is as much as three to four hours' difference in the time of heats over its most efficient operating condition.

By the construction embodied in the present invention the life of the regenerator is materially prolonged; there is less clogging of the checkers because the air and products travel at an increased velocity, and it is unnecessary to employ artificial draft by using any fan blast. Furthermore, the adjustment of the gas supply relative to the amount of air, and to the required flame conditions, is made possible by the provision of the movable nozzle and its parts, which are so arranged and designed as to accurately proportion the gas and air for any predetermined condition. The maintaining of a constant flame having a uniformly high velocity in connection with the foregoing construction results in saving of fuel and an extremely efficient furnace operation.

Having thus described my invention, I claim:

1. In a reverberatory furnace, a furnace head having a gas port and an air port surrounding the gas port and means to longitudinally move the gas port relatively to the air port.
2. In a reverberatory furnace, a furnace head having a gas port and an air port surrounding the gas port, means to move the gas port axially, the movement of said gas port also controlling the supply of gas thereto.
3. In a reverberatory furnace, a furnace head having air and gas flues, an air port tapered at its mouth, and receiving air from said air flue, a longitudinally movable gas

port within the air port and having an opening controlling the supply of gas thereto from said gas flue.

4. An end construction for regenerative open hearth furnaces having a throat opening into the hearth, an uptake flue leading to said throat and a member movable across the uptake toward or away from said throat to vary as desired the effective area of the throat, said member having a port facing the throat, and a channel leading to said port.

5. An end construction for regenerative open hearth furnaces having a throat opening into the hearth, and two uptakes communicating with said throat one of said uptakes having a portion movable toward or away from the throat to vary the effective opening between the hearth and the other uptake.

6. An end construction for regenerative open hearth furnaces, having a throat, an uptake with a nozzle end portion extending toward the throat, said throat and nozzle being relatively movable, a second uptake communicating with the throat and having a portion in rear of the throat into which the nozzle may be projected, relative movement between the nozzle and throat determining the effective area of the throat opening between the second uptake and the hearth.

7. An end construction for regenerative open hearth furnaces having a throat opening into a hearth, an uptake communicating with said throat, a nozzle extending through the wall of the uptake flue and toward the throat, a stationary uptake communicating with the nozzle, a carriage supporting the nozzle for movement relatively to the throat, and a seal between the nozzle and the stationary uptake for preventing gas leakage for all positions of the nozzle.

8. An end construction for regenerative open hearth furnaces, having a throat, an uptake communicating with said throat, a nozzle disposed axially of said throat and adapted to be moved away from the throat or toward and into the throat, and a second uptake communicating with the nozzle, the throat and first uptake being in unrestricted communication when the nozzle is in one position and being in communication through an annular opening when the nozzle is in a second position.

Signed at Philadelphia, in the county of Philadelphia, and State of Pennsylvania, this 13th day of June, 1921.

WILLIAM GAST.
